(57) **CLAIM**

The ornamental design of an earphone fin, as shown and described.

DESCRIPTION

FIG. 1 is a top back left side perspective view of an earphone fin according to our design;

FIG. 2 is a top front right side perspective view of the earphone fin shown in FIG. 1;

FIG. 3 is a bottom front left side perspective view of the earphone fin shown in FIG. 1;

FIG. 4 is a bottom back right side perspective view of the earphone fin shown in FIG. 1;

FIG. 5 is a right side view of the earphone fin shown in FIG. 1;

FIG. 6 is a front side view of the earphone fin shown in FIG. 1;

FIG. 7 is a left side view of the earphone fin shown in FIG. 1;

FIG. 8 is a back side view of the earphone fin shown in FIG. 1;

FIG. 9 is a top view of the earphone fin shown in FIG. 1; and, FIG. 10 is a bottom view of the earphone fin shown in FIG. 1.

The dashed lines shown in the various figures are provided for the purpose of illustrating unclaimed portions of the earphone fin and the dashed lines form no part of the claimed design.

1 Claim, 9 Drawing Sheets
